UNITED STATES PATENT OFFICE.

WILLIAM SPARKS, OF JACKSON, MICHIGAN.

DESIGN FOR A PUMP-CASING.

45,026.

Specification for Design.

Patented Dec. 9, 1913.

Application filed September 17, 1913. Serial No. 790,368. Term of patent 7 years.

To all whom it may concern:

Be it known that I, WILLIAM SPARKS, a citizen of the United States, residing at Jackson, Michigan, have invented and produced a new, original, and ornamental Design for a Pump-Casing, of which the following is a specification, reference being had to the accompanying drawings, forming a part thereof, in which—

Figure 1 is a front side elevation of the pump; Fig. 2 is a rear side elevation of the same; Fig. 3 is an end elevation of the same.

The design comprises a pump casing as

shown and adapted for use in connection with automobiles, engines or machines of any kind or in any connection in which a continuous circulation, propulsion or flow of the fluid is desirable.

I claim:

The ornamental design for pump casing, as shown.

WILLIAM SPARKS.
